UNITED STATES PATENT OFFICE.

JOHN BROOKS, OF MARIETTA, OKLAHOMA, ASSIGNOR OF ONE-HALF TO GEORGE E. SULLIVAN, OF MARIETTA, OKLAHOMA.

DEVICE FOR PREVENTING FLIES ENTERING HOUSES.

1,244,696.

Specification of Letters Patent. Patented Oct. 30, 1917.

Application filed May 8, 1915. Serial No. 26,826.

To all whom it may concern:

Be it known that I, JOHN BROOKS, a citizen of the United States, residing at Marietta, in the county of Love and State of 5 Oklahoma, have invented a new and useful Device for Preventing Flies Entering Houses, of which the following is a specification.

The device forming the subject matter 10 of this application is adapted to be employed for producing an agitation of the air adjacent the free edge of a door as the door is moved to an open position or closed, thereby to prevent flies from entering the 15 building for which the door constitutes a closure.

The invention comprises a rotating fan, and one object of the invention is to provide 20 novel means for actuating the fan, the door constituting the driving element for the actuating means.

It is within the province of the disclosure to improve generally and to enhance 25 the utility of devices of that type to which the present invention appertains.

With the above and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed, without departing from the spirit of the invention.

In the accompanying drawing:—

Figure 1 shows the invention in front elevation;

40 Fig. 2 is a side elevation, parts being broken away;

Fig. 3 is a top plan, parts being removed and broken away.

In the accompanying drawings, the numeral 1 indicates a door frame, and the 45 numeral 2 designates a door connected with the door frame 1 by hinges 3. Secured to the door frame 1 and projecting horizontally therefrom is a lower bracket 4, the same 50 preferably being of angular form. An upper bracket is provided, the same comprising coöperating angle members 5 and 6, the constituent members 5 and 6 of the upper bracket being secured to the door frame 1 55 adjacent the top of the door 2. The mem-

bers 5 and 6 of the upper bracket carry a shaft 7 supporting for rotation a horizontally disposed, grooved guide wheel 8. Mounted in the members 5 and 6 of the upper bracket is a shaft 9 supporting for 60 rotation a pinion 10. A rack bar 11 extends between the guide wheel 8 and the pinion 10 and is held in mesh with the pinion 10 by the guide wheel 8, as Fig. 2 will clearly disclose. Secured to the door 2 is a pivot 65 spindle comprising a base 50, a forwardly presented arm 12, and an upstanding finger 14, the rack bar 11 being provided at one end with an eye 15 adapted to be slipped over the finger 14, the construction being 70 such that one end of the rack bar 11 is pivotally assembled with the door 2.

The invention comprises a fan denoted generally by the numeral 17 and comprising any desired number of radial blades 18, the 75 fan 17 being vertically disposed, adjacent the free edge of the door 2. The lower end of the fan 17 terminates in a shaft 19 journaled in the bracket 4, and the upper end of the fan is equipped with a shaft 20 journaled for rotation in the member 5 of the upper bracket, the shaft 20 carrying a gear 80 wheel 21 meshing into the pinion 10.

As will be understood readily, when the door 2 is swung on its hinges, the rack bar 85 11 will be moved longitudinally, and will swing in a horizontal plane, the bar being held by the guide wheel 8 in mesh with the pinion 10, and motion being transmitted to the pinion 10, the pinion 10 imparting rotation to the fan 17 through the medium 90 of the gear wheel 21. The fan 17, therefore, will be rotated rapidly, whenever the door 2 is opened or closed the draft thus produced tending to prevent flies from entering the building for which the door 2 constitutes a closure. Owing to the interposition of the pinion 10 between the gear 95 wheel 21 and the rack bar 11, the speed of rotation of the fan 17 is increased. A 100 skilled mechanic will understand, however, without a specific delineation, but with the present drawings before him, that if desired, the pinion 10 may be omitted from the gear train whereby the rotating fan is 105 actuated.

Having thus described the invention, what is claimed is:—

In a device of the class described, a door frame; a hingedly mounted door; a lower 110

bracket secured to the frame; an upper bracket secured to the frame and including upper and lower parts, the upper part projecting outwardly beyond the lower part; 5 a fan substantially coextensive in length with the door, the lower end of the fan being journaled in the lower bracket, and the upper end of the fan being journaled in the upper part of the upper bracket, independently of the lower part of the upper bracket; a gear wheel carried by the upper end of the fan; a pinion located between the upper and lower parts of the upper bracket and journaled thereon, the gear wheel meshing 10 into the pinion; a grooved wheel located between the upper and lower parts of the upper bracket and journaled thereon; a rack bar having a smooth rear edge coöperating

with the grooved wheel, and provided in its forward edge with a rack meshing into the pinion; and a pivot spindle fixed to the door and upstanding above the upper edge of the door, the pivot spindle being provided with a shoulder on which the rack bar rests, the rack bar being mounted to swing on the spindle in a plane parallel to the plane in which the gear wheel and the pinion rotate. 20

25 In testimony that I claim the foregoing as my own, I have hereto affixed my signature in the presence of two witnesses.

JOHN BROOKS.
